(57) **CLAIM**

The ornamental design for a watch, as shown and described.

DESCRIPTION

FIG. 1 is a front view of a watch of the present invention when the band of the watch is in a fully extended configuration.

FIG. 2 is a rear view thereof.

FIG. 3 is a left view thereof.

FIG. 4 is a right view thereof.

FIG. 5 is a top view thereof.

FIG. 6 is a bottom view thereof.

FIG. 7 is a perspective view of thereof.

FIG. 8 is an enlarged front view of the watch when the band of the watch is in a curved configuration.

FIG. 9 is an enlarged perspective view of the watch when the band of the watch is in a curved and unlocked configuration; and,

FIG. 10 is an enlarged alternative perspective view of the watch when the body of the watch is shown unattached from the watch band and the band of the watch is in a curved and connected (or locked) configuration.

The broken lines in the drawings illustrate portions of the watch that form no part of the claimed design.

1 Claim, 9 Drawing Sheets
